Primary Examiner — Eric L Goodman*Assistant Examiner* — Sarah L Smith(74) *Attorney, Agent, or Firm* — Minder Law Group; Willy H. Wong(57) **CLAIM**

The ornamental design for a toy tow truck, as shown and described.

DESCRIPTION

FIG. 1 is a front view of a toy tow truck in accordance with the present invention.

FIG. 2 is a back view thereof.

FIG. 3 is a left view thereof.

FIG. 4 is a right view thereof.

FIG. 5 is a top view thereof; and,

FIG. 6 is a bottom view thereof.

The broken lines show portions of the toy tow truck that form no part of the claimed design.
